ADHESIVE DISPENSING GUN

Samuel R. Rosen, Lorain, Alan B. Reighard, Bay Village,
Robert G. Baker, Avon, and Lawrence E. Blazey, Bay
Village, Ohio, assignors to Nordson Corporation, Am-
herst, Ohio

Filed Feb. 12, 1970, Ser. No. 21,409

Term of patent 14 years

Int. Cl. D8—02

U.S. Cl. D8—30

FIG. 1

FIG. 2

FIG. 3

FIG. 4

FIG. 5

FIG. 6

FIG. 1 is a perspective view of an adhesive dispensing gun embodying our new design;

FIG. 2 is an elevational view taken from the side opposite that shown in FIG. 1;

FIG. 3 is a front elevational view thereof;

FIG. 4 is a top plan view thereof;

FIG. 5 is a rear elevational view thereof; and

FIG. 6 is a bottom plan view thereof.

We claim:

The ornamental design for an adhesive dispensing gun, as shown.
